US00D659545S

(12) **United States Design Patent**
Yourist et al.

(10) **Patent No.:** **US D659,545 S**
(45) **Date of Patent:** ** *May 15, 2012

(54) **CONTAINER**

(75) Inventors: **Sheldon E. Yourist**, York, PA (US);
Raymond A. Pritchett, Jr., Brogue, PA (US); **Matthew T. Gill**, Hellam, PA (US)

(73) Assignee: **Graham Packaging Company, L.P.**, York, PA (US)

(*) Notice: This patent is subject to a terminal disclaimer.

(**) Term: **14 Years**

(21) Appl. No.: **29/340,633**

(22) Filed: **Jul. 22, 2009**

(51) LOC (9) Cl. **09-01**

(52) U.S. Cl. **D9/552; D9/557**

(58) **Field of Classification Search** D9/516, D9/530, 537, 538, 540, 541, 543, 549, 551, D9/552, 556, 557, 559, 564, 569, 570, 575; 215/381-385; 220/660, 669, 679, 752

See application file for complete search history.

(57) **CLAIM**

The ornamental design for a “container,” as shown and described.

DESCRIPTION

FIG. 1 is a front perspective view of a container, embodying our design;

FIG. 2 is a side elevation view, the opposite side being a mirror image thereto;

FIG. 3 is a rear elevation view thereof; and,

FIG. 4 is a top plan view thereof.

The broken lines shown are included for the purpose of illustrating the unclaimed portions of the article and form no part of the claim.
